DESIGN FOR A FIGURE BOX

Daniel Jacoby, New York, N. Y.

Application November 4, 1941, Serial No. 104,023

Term of patent 3½ years

To all whom it may concern:

Be it known that I, Daniel Jacoby, a citizen of the United States and resident of New York city, in the county of New York and State of New York, have invented a new, original, and ornamental Design for a Figure Box, of which the following is a specification, reference being had to the accompanying drawing, forming a part thereof.

In the drawing:

Fig. 1 is a side elevational view of a figure box, showing my new design.

Fig. 2 is a top plan view of the same.

Fig. 3 is a front elevational view of the same.

Fig. 4 is a rear elevational view of the same.

I claim:

The ornamental design for a figure box, as shown.

DANIEL JACOBY.
